UNITED STATES PATENT AND TRADEMARK OFFICE
Certificate

Patent No. D. 572,963 S

Patented: July 15, 2008

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: John A. Gelardi, Kennebunkport, ME (US); Kenny Freitag, Cheshire, MA (US); and Andrew Siditsky, Simi Valley, CA (US).

Signed and Sealed this Sixth Day of September 2011.
